UNITED STATES PATENT OFFICE.

WILLIAM M. SHEEHAN, OF ST. LOUIS, MISSOURI, ASSIGNOR TO COMMONWEALTH STEEL COMPANY, OF ST. LOUIS, MISSOURI, A CORPORATION OF NEW JERSEY.

LOCOMOTIVE-FRAME.

1,114,193.

Specification of Letters Patent. Patented Oct. 20, 1914.

Application filed April 21, 1914. Serial No. 833,442.

To all whom it may concern:

Be it known, that I, WILLIAM M. SHEEHAN, a citizen of the United States, residing at the city of St. Louis, State of Missouri, have invented a certain new and useful Improvement in Locomotive-Frames, of which the following is a full, clear, and exact description, such as will enable others skilled in the art to which it appertains to make and use the same, reference being had to the accompanying drawings, forming part of this specification, in which—

Figure 1 is a top plan view of a locomotive frame of my improved construction. Fig. 2 is a side elevational view of the frame. Fig. 3 is a section taken approximately on the line 3—3 of Fig. 1. Fig. 4 is a transverse section taken approximately on the line 4—4 of Fig. 1. Fig. 5 is a transverse section taken approximately on the line 5—5 of Fig. 1.

My invention relates generally to locomotive frames and more particularly to a one piece rear extension for the main frame of the locomotive.

Heretofore in the construction of locomotive frames and particularly the rear frame or extension, it has generally been the practice to construct said rear frame or extension of separate castings or forgings, which after being properly assembled, are connected to the main frame by machine-fit bolts. Such construction has many disadvantages for the reason that the strains and constant vibration developed when the frame is in service tends to loosen the joints between the assembled parts, thereby destroying the stability of the frame and the alignment and position of the various bearings and brackets which receive certain devices particularly associated with and carried by the rear frame or extension. Furthermore, making the frame in several pieces, necessitates a considerable amount of machine work and other finishing; likewise the setting of a large number of rivets and bolts.

It is the principal object of my invention to overcome the objectionable features just mentioned by casting the rear frame or extension in a single piece, and forming integral therewith the necessary brackets and bearings, thus producing a very strong, rigid and substantial structure which, in service, effectually resists all strains to

which it is ordinarily subjected, and which is not affected by the constant vibration developed in service.

With the above and other objects in view, my invention consists in certain novel features of construction and arrangement of parts, hereinafter more fully described and claimed.

As shown in the accompanying drawings, my improved rear frame or extension includes a pair of parallel side members 10, which may be of any desired cross sectional shape, such as for instance, channels having outwardly presented flanges. The forward ends of the webs of these side members are devoid of flanges, and their outer faces are preferably machined and provided with bolt holes in order to be properly connected to the side frames A of the main frame of the locomotive. The forward ends of the members 10 are united by transversely disposed integral webs or plates 11, and formed integral with the inner edges of these plates is a transversely disposed vertical wall or plate 12 which serves as a support and point of connection for the front end of the fire box.

Formed integral with the forward portions of the members 10 are outwardly projecting brackets 13, in the outer portions of which are formed apertures 15 adapted to receive brake hanger pins. Formed integral with the lower portions of the members 10 and near their front ends are outwardly projecting horizontally disposed plates 16 which serve as supports for equalizer fulcrums. Formed integral with and connecting the forward portions of the members 10 and a short distance to the rear of wall 12 is an inclined plate 17 which, in addition to forming a cross tie, serves as a portion of the front wall of the front ash pan B, the upper edge of the front wall of the ash pan proper being attached in any suitable manner to the lower edge of this transverse wall. (See dotted lines, Fig. 2.) Formed integral with and arranged between the central portions of the members 10 is a plate 18 which is arched or substantially of inverted U-shape in cross section, and said arched plate in addition to forming a tie between the central portions of the members 10 serves as portions of the walls of both front and rear ash pans.

The upper edge of the rear wall of the

ash pan B is attached to the lower front edge of the arched plate 18 and the rear wall of the front ash pan C is attached to the lower front edge of said arched plate.

5 The upper edges of the side walls of pans A and B are attached in any suitable manner to the lower flanges of side members 10.

Formed integral with and projecting outwardly from the members 10 and at points 10 between the plates 17 and 18 are pairs of brackets 19, the same being transversely perforated in order to receive the pins which are utilized for attaching the spring yokes D to the frame. Formed integral with the 15 members 10 to the rear of the arched plate 18 are outwardly projecting horizontally disposed plates or brackets 20 and formed integral with the forward outer corners thereof are pairs of lugs 21 which are transversely perforated in order to receive pins utilized for attaching the lower ends of 20 spring hangers E. Formed integral with the undersides of the plates 20 and in longitudinal alignment with the brackets 19 are 25 brackets 22 which are perforated in order to receive the rear pair of spring yoke attaching pins.

A transversely disposed inclined plate 23 is arranged between the members 10 to the 30 rear of plate 18, thus forming a portion of the rear wall of the rear ash pan C, and the upper edge of the rear wall of the body of this ash pan is connected in any suitable manner to the lower edge of said inclined plate. In my improved frame those portions of the members 10 between the transverse members 17, 18, and 23 form side walls 35 for the upper portions of the ash pans.

Formed integral with the members 10 to 40 the rear of the inclined wall 23 is a transverse wall or plate 24, the lower portion of which is provided with a forwardly projecting flange 25 and this wall and flange serve as a support and point of attachment for the 45 central portion of the rear of the fire box. Formed integral with the rear portions of the plates 20 are upwardly projecting transversely disposed ribs or flanges 26, which are substantially in transverse alignment with 50 the wall 24, and these ribs or flanges serve as supports and points of attachment for the outer portions of the rear end of the fire box.

The rear portions of the members 10 are 55 united by an integral structure comprising a horizontally disposed top plate 27, bottom plate 28, intermediate plate 29, and rear end plate 30. The bottom plate 28 is preferably located in a plane a short distance below the undersides of the members 10, and are 60 ranged between said bottom plate and intermediate plate 29 are longitudinally disposed webs or walls 31. The space between these walls and the bottom and intermediate plates is occupied by the rear draw bar, the same 65 being connected to the frame by means of a

suitable pin which passes through openings 32 which are formed in the bottom and intermediate plates. Formed integral with the end plate 30 is a housing 33, open at its outer end and which serves as a buffer pocket. The rear plate 30 is extended upward above the top plate 27, to form a transversely disposed rib or flange 34 which serves as a seat and point of attachment for the cab bracket F.

Formed integral with the rear ends of the members 10 are depending lugs or brackets 35 which are transversely perforated in order to receive attaching pins for the safety chain clevises.

The rear portion 28a of the bottom plate 28 serves as a seat and point of attachment for the truck centering device.

A rear extension for locomotive frames of my improved construction is very strong, can be readily produced inasmuch as it can be easily cast in a single piece, and by forming integral with said frame a number of essential brackets, bearings and the like much time, labor and consequent expense incident to the attaching of separate parts can be saved. Furthermore, the elimination of joints in the frame does away with structural weaknesses which invariably develop when an assembled or fabricated structure is subjected to service strains and vibrations.

A one piece casting can be produced in much less time and with less labor than a frame built up from a number of structural shapes and castings, which are united by bolts, rivets and the like, and it has been demonstrated in practice that an extension frame cast in one piece while of lighter weight has much greater strength and rigidity than a built up frame.

It will be readily understood that minor changes in the size, form and construction of the various parts of my improved extension frame can be made and substituted for those herein shown and described, without departing from the spirit of my invention, the scope of which is set forth in the appended claims.

I claim:

1. A rear frame for locomotives cast in a single piece and comprising a pair of side members and a series of transversely disposed members, certain of which are inclined.

2. A rear frame for locomotives cast in a single piece and comprising side members, and a series of transverse members, one of which forms a portion of the front wall of one of the ash pans associated with said frame.

3. A rear frame for locomotives cast in a single piece and comprising side members, and a series of transverse members, which constitute parts of the front and rear walls of the ash pans associated with the frame.

4. A rear frame for locomotives cast in a single piece and comprising side members, a pair of transversely disposed inclined walls, and a transversely disposed arched plate, 5 which inclined walls and arched plate constitute parts of the front and rear walls of the ash pans associated with the frame.
5. A rear frame for locomotives cast in a single piece and comprising side members, 10 a series of transversely disposed members, and brackets which are adapted to receive spring yoke pins.
6. A rear frame for locomotives cast in a single piece and comprising side members, 15 a series of transversely disposed members, and a plate which forms a seat and point of attachment for the truck center device.
7. A rear frame for locomotives cast in a single piece and comprising side members, 20 a series of transversely disposed members, brackets projecting outwardly from the side members, pairs of perforated lugs on said brackets adapted to receive spring yoke pins, and pairs of perforated lugs on said brackets, 25 which are adapted to receive spring hanger pins.
8. A rear frame for locomotives cast in a single piece and comprising side members, a series of transversely disposed members, 30 and brackets projecting outwardly from the side members, portions of which brackets serve as seats and points of attachment for the rear end of the fire box of the locomotive.
9. A rear frame for locomotives cast in a single piece and comprising side members, 35 a series of transversely disposed members, a rear end wall, and a housing on said rear end wall, which housing is provided with a buffer pocket.
- 40 10. A rear frame for locomotives cast in a single piece and comprising side members, a series of transversely disposed members, and a rear end plate, the upper portion of

which forms a seat and point of attachment for the cab bracket of the locomotive. 45

11. A rear frame for locomotives cast in a single piece and comprising side members, a series of transverse members, certain of which constitute portions of the front and rear walls of the ash pans associated with the frame, pairs of perforated lugs adapted to receive brake hanger pins, pairs of perforated lugs adapted to receive spring yoke pins, pairs of perforated lugs adapted to receive spring hanger pins, a bracket adapted to receive the truck centering device, a rear end plate, a housing thereon, which housing serves as a buffer pocket, a flange adapted to receive the cab bracket of the locomotive, and flanges adapted to form seats and points of attachment for the locomotive fire box. 55 60

12. A rear frame for locomotives cast in a single piece and comprising side members, and a series of transverse members, parts of which side members and certain of which 65 transverse members form parts of the walls of the ash pans associated with the frame.

13. A rear frame for locomotives cast in a single piece and having parts which constitute portions of the walls of the ash pans 70 which are associated with the frame.

14. A rear frame for locomotives cast in a single piece and comprising side walls, parts of which constitute portions of the side walls of the ash pans associated with the 75 frame, and transverse members which constitute parts of the end walls of the ash pans.

In testimony whereof I hereunto affix my signature in the presence of two witnesses, 80 this 18th day of March, 1914.

WILLIAM M. SHEEHAN.
